FUR STEAM GLAZER

Harris W. Moss, Phoenix, Ariz.

Application September 5, 1951; Serial No. 245,219

4 Claims. (Cl. 69—20)

1

This invention concerns steam fur glaziers.

If a spray discharge of dry steam, issuing from a nozzle under a pressure of from 45 to 85 pounds per square inch, be directed against and onto the fur of a garment held on a coat hanger, or the like, and the nozzle moved up and down with a series of vertical sweeping strokes directed over the garment, the oils and fats contained in the fur and pelt will be melted and brought to the surface, and the outer hair glazed. At the same time dirt within the hair will be blown away, and the hairs fluffed and given a new set. The steam used must, however, be perfectly dry, and means must be provided for removing condensed water as fast as it is formed, and for keeping it from entering the discharge or glazing nozzle.

In view of this, one of the objects of my invention is to provide a steam glazing nozzle with means for trapping out any and all water of condensation, and with means for removing condensed water and with means for controlling the flow of steam as desired.

Another object is to provide a glazing nozzle which can be held in the hand with means for removing water trapped from the steam flowing to it, and with means for connecting to a source of steam supply, and for controlling the flow of steam therethrough within easy reach of the hand of the user.

Other objects will appear hereinafter.

I attain the foregoing objects by means of the devices, parts, and combination of parts shown in the accompany drawing, in which—

Figure 1 is a side elevation of my improved glazing nozzle;

Figure 2, a longitudinal sectional elevation thereof;

Figure 3, a cross section thereof taken on line 3—3, of Figure 2;

Figure 4, a perspective view of the device showing one manner of its use; and

Figure 5 of the steam inlet pipe and condensing screen which are contained within said nozzle body.

Similar numerals refer to similar parts in the several views.

The complete glazing nozzle is indicated by numeral 1. A steam drying cylinder 2 closed at each end has a nozzle tube 3 projecting outward from its outer end. This tube is eccentrically positioned with reference to the axis of cylinder 2, and extends into the upper interior portion of the cylinder with its inner end spaced away from the interior walls thereof.

A steam inlet tube 5 extends axially into the

rear end of cylinder 2. Its inner end is closed, but steam escapes from ports 14 drilled radially along the sides of its inwardly extending portion. The outer end of this tube is threaded and quick opening automatic closing valve 7 screwed onto it. The plug 10 of this valve closes in the direction of steam flow through it, and this plug is unseated and opened by handle 12. An insulated holding handle 8 extends axially from the body of valve 7, and is alined with the axis of tube 5. The valve inlet is connected to a steam supply hose 30.

To condense, collect, and hold back any water issuing with the steam from holes 14 the inner portion of tube 5 is enclosed in a screen 16 which is bent to have a substantially triangular section. The top portion 26 is flat and extends substantially across the middle of the interior of cylinder 2 throughout its length. Each side is then bent downwardly and inwardly along lateral folds 27, which contact the inner wall of the cylinder. The two bottom edges of the screen do not meet but are separated slightly to form a longitudinal condensate channel along the bottom of the cylinder connecting drain vents 17 and 18 which are positioned at each end thereof. A dry steam chamber 15 is thus provided within the horizontal upper portion of the interior of cylinder 2 above the flat top 26 of screen 16. Nozzle tube 3 projects into this chamber. A condensate chamber 25 is likewise formed in the bottom portion of said cylinder.

Drain vents 17 and 18 are provided with drain tubes 21 and 22 and these are then joined to drain hose 23. Tube 24 which connects tube 21 to drain hose 23 extends rearwardly at a downwardly slanting angle so that water will drain from the front vent 17 even when cylinder 2 is tilted downward, as shown in dotted outline, Figure 4. Drain hose 23 and steam supply hose 30 are brought together beneath handle 8 by clips 31. Steam hose 30 thence leads to a source of steam, and drain tube leads to a vessel 40, or other means of disposal.

In use a garment 35 (a fur coat for example) is hung on a hanger 33 and the glazing nozzle held by handle 8 while dry steam is blown into the fur or fabric from tube 3 by opening valve 7. The device is moved with an up and down stroke over the garment. At the top of the stroke condensed water drains through tube 18; at the bottom of the stroke, when the cylinder 2 is tilted forward and downward, water drains out through tubes 21 and 24 to hose 23.

When cylinder 2 is cold and valve 7 is first

opened, both steam and condensate run out of the drains. These drains each have a slightly greater size than tube 3. As the parts of the device heat up water is driven out through vents 17 and 18 and then steam follows the water condensate. Meanwhile steam issues from nozzle tube 3. Since all condensate is screened from it and drained away all steam issuing from tube 3 is dry. After tube 2 is thoroughly heated damp steam (along with some condensate) issues from drain hose 23 whenever valve 7 is opened. Only dry steam (scarcely visible) issues from tube 3. It is to be understood that valve 7 is opened sufficiently so that, as the steam expands in cylinder 2, there is sufficient steam pressure to force condensate from vents 17 and 18, and, at the same time provide an adequate flow of dry steam through tube 3 to accomplish glazing as and for the purposes here intended.

The handle 8 is grasped in the hand of the user so that cylinder 2 normally extends horizontally. It is raised and lowered angularly from this position so that nozzle tube 3 is first directed upwardly and then downwardly; the upper half of the interior of tube 2, however, is always above the lower half and condensate never enters the chamber 26.

The composite structure of the nozzle, as above described enables the user to easily and quickly glaze furs with a minimum of effort. The structure insures that only dry steam, such as is required for glazing, exits from nozzle tube 3, and thus the device is very efficient for the purposes intended.

Various modifications and substitutions of parts are obvious. Furthermore, other uses, such as processing certain woolen fabrics, or the like, may be made of the device, and it is not limited to the use on furs above described.

I claim:

1. A steam fur glazer consisting of a substantially horizontally disposed steam drying cylinder having a closed front end and rear end, an axially positioned steam inlet tube projecting into its interior from its rear end, said tube being closed at its inner end and provided with steam outlet ports along its sides, and a nozzle tube eccentrically disposed above said steam inlet tube projecting from the upper horizontal portion of the interior of said cylinder outward through the outer end thereof, and condensate vents in each end of the bottom thereof; a screen extending longitudinally within the middle of said cylinder dividing it horizontally to form a dry steam chamber in the upper portion thereof and surrounding said steam inlet tube; a valve having an insulated handle extending rearwardly in alined relation to said steam inlet tube, a valve plug opening lever over said handle, and an inlet adapted to be connected to a source of steam under pressure; condensate drain tubes connecting the front and rear drain vents of said cylinder to a drain hose, said front drain tube extending angularly rearwardly and downwardly.

2. A steam fur glazer consisting of a substantially horizontally disposed cylinder having a rear closed end and an outer closed end and provided with a steam inlet tube extending axially into the interior thereof through said rear end having steam vents, along its sides and closed at its inner

end and drain vents at each end of the bottom thereof; a screen within said cylinder having a flat top disposed above said steam inlet tube extending horizontally throughout the length of the interior of said cylinder, dividing it to form a dry steam chamber in the upper portion thereof and a condensate compartment in lower portion thereof, and having its sides bent downwardly and inwardly forming lateral folds contacting the inner walls of said cylinder and having the depending edges thereof spaced apart to form a condensate channel along the bottom of said cylinder; a nozzle tube projecting outward through said outer cylinder end, eccentrically disposed above said steam inlet tube, and extending from said dry steam chamber; a valve attached to said steam inlet tube having a plug closing in the direction of the flow of steam therethrough, a handle extending rearwardly in alined relation with said steam inlet tube, an opening lever extending over said handle, and an inlet adapted to be attached to a steam supply hose; and drain tubes connecting said drain vents to a drain hose, said tube connecting the drain vent at the forward end of said cylinder extending angularly rearwardly and downwardly to drain the forward end of said cylinder when said cylinder is tilted downward at its front end.

3. A steam fur glazer composed of a steam drying cylinder closed at its front and rear end and provided with drain vents at the front and rear of its bottom side, an axially extending steam supply tube extending into its interior having a plurality of laterally opening steam vents; a metal screen surrounding said steam supply tube within said cylinder; a steam nozzle tube extending from the upper portion of said cylinder above said screen and protruding from the front end thereof; a lever operating valve attached to the rear outer end of said steam supply pipe having an inlet adapted to be attached to a steam supply hose and a rearwardly projecting insulated handle, and drain vent tubes connecting the drain vents of said cylinder to a drain hose.

4. A steam fur glazer composed of a steam drying cylinder closed at its front and rear end and provided with drain vents at the front and rear of its bottom side, an axially extending steam supply tube extending into its interior having a plurality of laterally opening steam vents; a metal screen surrounding said steam supply tube within said cylinder; a steam nozzle tube extending from the upper portion of said cylinder above said screen and protruding from the front end thereof; a lever operating valve attached to the rear outer end of said steam supply pipe having an inlet adapted to be attached to a steam supply hose and a rearwardly projecting insulated handle, and tubes connecting the front and rear drain vents of said cylinder to a drain hose clamped to said steam supply hose below said handle; the tube connecting said front drain extending angularly rearward and downward to its place of juncture with the tube extending from said rear drain, so that the front end of said cylinder will be readily drained when said cylinder is tilted with its front end extending angularly downward.
